Primary Examiner — Jae Liang*Assistant Examiner* — Jane Yoon(74) *Attorney, Agent, or Firm* — Ashley D. Johnson; Dogwood Patent and Trademark Law(57) **CLAIM**

The ornamental design for a contact lens case, as shown and described.

DESCRIPTION

FIG. 1 is a top-left-front perspective view of a contact lens case, showing my new design.

FIG. 2 is a front plan view of the contact lens case of FIG. 1.

FIG. 3 is a left side view of the contact lens case of FIG. 1. FIG. 4 is a rear plan view of the contact lens case of FIG. 1. FIG. 5 is a right side view of the contact lens case of FIG. 1.

FIG. 6 is a top view of the contact lens case of FIG. 1; and, FIG. 7 is a bottom view of the contact lens case of FIG. 1. The broken lines shown throughout the figures illustrate portions of the contact lens case that form no part of the claimed design.

1 Claim, 7 Drawing Sheets(56)
